UNITED STATES PATENT OFFICE.

LUDWIG HOLLAND-LETZ, OF CROWN POINT, INDIANA, ASSIGNOR TO THE LETZ MANUFACTURING COMPANY, A CORPORATION OF INDIANA.

GRINDING MILL.

Application filed March 15, 1926. Serial No. 24,668.

This invention relates to a grinding mill which is capable of reducing porous materials, but is particularly adapted for fibrous material.

5 One of the objects of the present invention is to provide an improved form of grinding mill which is simple in construction and efficient in operation.

10 A further object of the invention is to provide a novel and improved form of grinding mill in which a single rotary member performs a plurality of functions such as cutting the material being fed into the mill, feeding the material thus cut and grinding 15 the material fed thereby.

15 A further object of the invention is to provide an improved form of grinding mill having a combination cutting, feeding and grinding member which is adapted to co-operate with stationary portions of the mill for recutting the material after the first cutting operation.

20 A further object of the invention is to provide an improved feeding mechanism in combination with a grinding mechanism whereby certain portions or ribs of the rotating member co-operate with certain portions of the stationary member to alternately feed and cut the material during each cycle of operation of the rotating member.

25 A still further object of the invention is to provide a novel construction of a grinding mill in which the tension or pressure between the rotating member and the stationary buhr 30 may be adjusted for grinding the material into a fine, medium or coarse form.

35 These and other objects are accomplished by providing a construction and an arrangement of the various parts in the manner hereinafter described and particularly pointed out in the appended claims.

40 Referring to the drawings, Fig. 1 is a rear elevational view of my improved grinding mill.

45 Fig. 2 is a side elevational view partly in section, taken on the lines 2—2 in Fig. 1.

Fig. 3 is a top plan view showing the construction of my improved form of rotary cutting, feeding and grinding member.

50 Fig. 4 is a top plan view showing the construction of my stationary buhr with only a portion of the shearing or cutting projection shown thereon.

55 Fig. 5 is a partial fragmentary cross sectional view taken on the line 5—5 in Fig. 1

showing a section of one of the cutter knives and its relative position to the stationary portions of the mill adjacent the rotating member or knife.

Fig. 6 is a fragmentary cross sectional view 60 taken on line 6—6 in Fig. 1 showing the construction of the mechanism for adjusting the pressure tension between the grinding buhrs of the mill.

Fig. 7 is a reduced bottom plan view 65 showing the construction of the adjusting collar and indicator for varying the pressure or tension between the grinding buhrs.

Fig. 8 is a side elevational view of the bearing sleeve which rotatably supports the 70 rotating member, and

Fig. 9 is an end elevational view showing 75 the construction of the bearing sleeve shown in Fig. 8.

For the purpose of illustration I have 80 shown my improved grinding mill embodied in a hand operated device, but it will of course be readily understood that a pulley may be easily substituted for the crank handle shown in the drawing so as to make the same power 85 operated.

In illustrating one embodiment of my invention I have shown the same as comprising 90 a frame portion 10 which is provided with laterally extending ears or lugs 11, which in 95 turn, are provided with longitudinally extending slots 12 for the reception therein of bolts 13 for securing the mill to a stationary support which may be any suitable table or stand 14. The frame 10 is preferably circular or disc-shaped in form, as shown at 15 and is provided with a concentrically arranged rib as shown at 16 for reinforcing and strengthening the same. Extending about the periphery of the disc-shaped portion 15 100 and preferably at right angles with respect thereto is an annular flange 17 so as to form a disc-shaped portion on the inner side of the frame. Extending at regular intervals on the inner side of the disc-shaped frame member 15 are a plurality of cutter bars 18, 19, 20 and 21. The cutter bars 18, 19 and 20 are 105 constructed so that their inner portions form the arcs of a circle as shown at 18', 19' and 20', respectively, which may be said to be 110 tangent to a common circle concentric with the axis of the disc-shaped member 15 and have their outer ends in the form of a straight line, as shown at 18'', 19'' and 20'', respectively, which is tangent to a common circle 115

120

concentric with the first circle, but substantially larger than the first circle. These cutter bars extend inwardly from the base of the disc-shaped member 15 and have their cutting edges lying in a plane which is common to the inner edge 21 of the annular flange 17. The cutter bar 18 in co-operation with the cutter knife hereafter described forms the initial cutting mechanism for cutting the material as it is fed into the mill and the cutter bars 19, 20 and 21 in co-operation with the cutter knives on the rotating member form the recutting mechanism. These cutter bars have their upper surfaces 21' inclined so that the material will slide off the bars, see Fig. 5. The cutter bar 21 extends substantially on a straight line or on a line tangent with a relatively small circle which would lie concentric with the axis of the disc-shaped member 15. Extending upwardly and outwardly at an angle with respect to the horizontal is a hopper socket 22 which may have attached thereto a hopper 23. Extending below the hopper socket and preferably as a continuation of the hopper is an outwardly extending wall 24 which forms a pocket for receiving and holding the material fed in through the hopper. Extending through the disc-like member 15 and communicating with the pocket 24 and hopper is an opening 25. This opening passes through the disc-portion 15 and is in the form of substantially the shape of a heart, one edge of which is bounded by the cutter bar 18 and the other edge of which is bounded by the curved portions 26.

One of the important features of my improved grinding mill is the provision of a novel construction of a rotating member which performs the function of cutting the material up and passing the same therethrough, thence feeding it into the shearing or grinding buhrs. This mechanism comprises a rotating member 27 which is mounted concentrically with the axis of the stationary frame member 10 and rotatable with respect thereto. This member 27 is provided with a hub portion 28 in the center thereof and with a plurality of curved knives 29. These knives 29 are located on one side of the rotating member 27 and are arranged at intervals of 120 degrees apart. These knives 29 like the cutter bars 18, 19 and 20 have their inner ends in the form of arcs of circles which might be said to be tangent to a relatively small circle concentric with the axis of rotation of the rotating member and their outer ends in the form of arcs of relatively larger circles, as clearly shown in Fig. 3. These knives 29 on the rotating member 27 are curved in a reverse direction to the co-operating cutter bars 18, 19 and 20 so that the outer portions of the cutter knives and co-operating cutter bars press and convey the material inwardly toward the axis of the rotating

member so that the material is confined to a reducing elliptical form where the material is finally sheared off adjacent the inner ends of the cutter members. It is, of course, understood that the cutting edges of the knives 29 move in a plane contacting with the plane of the cutting edges of the bars 18, 19, 20 and 21, so as to effect a shearing action between these cutting members. The cutting knives 29 on the rotary member 27 are arranged so as to form pockets or chambers therebetween, through the medium of which the material is carried from cutter bar to cutter bar of the frame 10, on each cycle of operation of the rotary member for the re-cutting operation of the material. On each occasion that a pocket or chamber passes the heart-like opening 25, in the frame 10, an additional supply of material is added to the particular chamber. This operation is continued throughout the operation of the machine as material is being fed into the hopper. The rotating member 27 has three apertures somewhat irregular in shape as shown at 30 extending therethrough, and located adjacent the inner curved portions of the cutting knives 29 for permitting the material as it is sheared between the cutting knives and the cutter bars to pass on through the rotating member from where it is fed by the mechanism hereafter described to the shearing and grinding buhrs. The cutter knives are preferably tapered or inclined rearwardly with respect to the direction of travel of the rotating member as shown at 31 so as to present a sharp cutting edge 32 to each of the cutter bars and also for the purpose of directing and forcing the material inwardly or through the apertures 30 as the material is cut by the cutting knives as shown in Fig. 5. Extending from the hub portion 28 and on the side of the rotating member 27 opposite the knives 29 are three main feeding ribs 33 which have broken extended portions as shown at 33'. These broken extended portions 33' as well as the outer portions of the main feeding ribs 33 as shown at 34 perform the alternate functions of feeding and shearing when co-operating with the co-acting ribs on the stationary member as will hereinafter be described. These main feeding ribs 33 extend from adjacent the inner edges of the apertures 30 as shown at 34 to the outer periphery of the rotating member and are in the form of substantially cycloidal curves. By this construction it will be readily seen that as the cutter knives 29 in co-operation with the cutter bars on the stationary frame member 10 cut the material the inclined portion 31 of the knives together with the incoming material forces the material through the apertures 30 after which the inner portions of the feeding ribs engage the material thus cut and in co-operation with certain ribs hereinafter described forces the material to

ward the outer periphery of the buhrs. Extending between the main feeding ribs 33 and located on the outer portion of the rotating member are a plurality of supplemental alternate feeding and shearing ribs 35 which occupy a symmetrical position with respect to the main feeding ribs 33 so as to properly space these supplemental feeding and shearing ribs at substantially equal distances from each other. These supplemental ribs 35 are preferably broken. Interposed between each of the broken portions of these supplemental feeding and shearing ribs 35 and also between the main ribs 33 and extended portion 33' are transversely positioned symmetrically arranged shearing ribs 36. These shearing ribs 36 co-act with portions of the feeding ribs on the complimentary buhr to shear the material passing therebetween. Co-operating with the rotary member 27 and positioned concentrically with the same is a stationary buhr 37. The stationary buhr 37 is provided with a hub 38 and has four main feeding ribs 39 extending from the hub 38 to the periphery, and are positioned in the reverse direction to that of the main feeding ribs 33 on the rotating member 27. The main ribs 39 have broken extensions as shown at 39' and 40' which perform the alternate function of feeding and shearing when co-acting with the co-operating ribs on the rotary member. These main feeding ribs 39 are substantially in the form of a cycloidal curve and are adapted to co-operate with the three main feeding ribs 33 on the rotary member 27 for forcing and feeding the material cut by the knives in a direction toward the periphery of the buhrs to the grinding and shearing portions of the stationary and rotating members. In this connection, one of the important features of my improved grinding mill is the employment of three main feeding ribs on the rotating member which co-operate with four main feeding ribs on the stationary member so that only one of the feeding ribs on the rotating member co-operates with its co-acting feeding rib on the stationary member, thereby permitting only one pair of co-acting ribs to perform their function at one time. In other words, by reason of having only three feeding ribs on the rotating member and four feeding ribs on the stationary member, these ribs alternate in their co-operation with the corresponding stationary feeding ribs for feeding the material to the grinding buhrs, thereby relieving the mill of an irregular excessive strain and the operator of intermittent burden of operating the machine than would be occasioned by having the number of feeding ribs on the rotating member and the stationary member equal in number. This construction of employing an unequal number of feeding ribs on the rotary member and the stationary member, respectively, progressively brings the co-acting ribs into operation and equally distributes the strain necessary to drive the rotating member throughout the entire cycle of operation of the rotating member and thereby effects the very efficient and smooth operation of the mill.

It will be noted that by having the feeding ribs reversely curved on the rotating member and stationary member, respectively, that as the rotating member is revolved the action of the co-operating feeding ribs in crossing one another produces a camming action and forces or presses the material between the contiguous edges of the ribs in a direction outwardly toward the periphery where it is engaged by the alternate feeding and shearing ribs of the respective members. The stationary member 37 is provided between each of the feeding ribs 39 with a plurality of symmetrically arranged supplemental alternate feeding and shearing ribs 40. These ribs 40 are broken, as clearly shown in Fig. 4, and have interposed between the broken portions transversely extending shearing or grinding ribs 41.

It will be noted that when the alternate feeding and shearing portions of the main ribs 33, as indicated at a and the extended portions 33' of the main feeding ribs 33 as well as the supplemental feeding ribs 35 of the rotating member 27 are cooperating with the transverse ribs 41 of the stationary member 37, a shearing of the ribs 33 and extensions 33' as well as the supplemental feeding ribs 35 co-act with the corresponding feeding ribs 39, 39', 40 and 40' of the stationary member 37 a feeding or forcing of the material toward the periphery of the members is taking place. It will also be noted that when the main feeding member 39, extensions 39' and 40' as well as the supplemental feeding ribs 40 co-act with the transverse ribs 36 on the rotary member a shearing of the material takes place. As previously pointed out, this action of feeding and shearing is alternate and the fact that there are a series of seven ribs on the stationary member and a series of eight ribs on the rotary member causes such a relative displacement of the series of the ribs on the two faces that in each section there can only be one pair of the series actually shearing at a time, so that the resistance offered to the shearing action is spread out over the complete cycle of operation as to produce a practically continuous resistance in the machine, instead of an intermittent one. It will also be noted that a further spreading out of the resistance to the shearing action is secured by the fact that the co-operating shearing ribs of one buhr are diverging a little from the co-operating feeding ribs of the other buhr as to come into register by their relative movement so that a progressive shearing action is produced between each pair of ribs. For a more detailed description of the construction and operation

of this novel form of grinding buhr see my copending applications Serial Nos. 753,202 filed December 1, 1923 and 20,954, filed April 6, 1925, respectively.

5 The stationary member 37 is provided with a laterally projecting lug 42 which is adapted to engage a bracket 43. The bracket 43 is provided with a slot 44 on one side thereof for the reception of the lug 42 and on the other 10 side thereof is provided with an aperture for the reception of a bolt 45 which secures the bracket to a portion of the frame adjacent the socket 22. This lug 42 on the stationary member 37 secures the member against rotation and at the same time permits the member 37 to adjust itself with respect to the rotary member. The rotating member 27 is rotatably supported on the main frame 10 by a bearing sleeve 46. The bearing sleeve 46 is 15 provided with an enlarged circular portion 47 which forms a shoulder 48 for engaging a finished portion 49 of the rotating member 27. The sleeve 46 extends through the aperture 50 in the rotating member 27 and also through 20 the aperture 51 of the stationary member 37. The sleeve 46 is provided with a longitudinal extending bore 52. Formed in the enlarged portion 47 of the sleeve 46 and concentrically arranged with respect to the bore 52 is an annular recess 53 which forms a seat for a compression spring 54. The enlarged portion 47 of the sleeve 46 is further provided with laterally projecting rectangular lugs 55 25 on the opposite sides thereof which are adapted to be seated in recesses or key-ways 56 formed in the hub 57 of the frame member 10. These key-ways 56 engage the lugs 55 and prevent the sleeve 46 from rotation with respect to the main frame 10. The main 30 frame member 10, rotary member 27 and stationary member 37 are held in their relative operative positions by a carriage bolt 58 which extends through a washer 59 and sleeve 46 on one end and through an adjusting collar 60 and thumb nut 61 on the other end, the 35 adjusting nut 61 being in threaded engagement with the threaded portion of the bolt.

It will be noted by referring to Fig. 2 of the drawing that the end of the sleeve 46 as 40 shown at 46' stops short of the washer 59 so that the sleeve 46 may move longitudinally a relatively short distance with respect to the stationary portions of the mill so that the pressure of the spring 54 is brought to bear 45 on the grinding surfaces of the buhrs. It will also be noted that the finished portion 49 of the hub 28 of the rotating member is sufficiently large to engage the inner finished surface 57' of the hub of the frame member 10 so as 50 to limit the retractile movement of the grinding surfaces with respect to each other.

Another important feature of my improved grinding mill is the provision of a 55 novel means for permitting an adjustment of the pressure between the surfaces of the

grinding buhrs so that when fibrous material, such, for example, as oats or hay is to be ground a relatively greater pressure between the grinding surfaces of the buhrs is required. This mechanism includes the adjustable collar 60 which is provided with a plurality of depressed recesses 62, 63 and 64. These recesses are arranged in a series of three corresponding recesses arranged about the bottom of the collar at intervals of about 70 one hundred and twenty degrees apart. The recesses 62 are relatively shallow with the recesses 63 and 64 of graduated increasing depth so that when the collar is positioned in its operative position one set of the recesses such as 62 engage co-operating lugs 65 which register with the recesses in the collar. When it is desired to grind porous or non-fibrous materials the collar is positioned so that the shallowest recesses 62 engage or 75 register with the lugs 65 formed on the frame member 10, and when it is desired to reduce a relatively harder or fibrous material the collar 60 is adjusted so that the intermediate recesses 63 engage or register with the lugs 65. When it is desired to reduce exceptionally hard, fibrous or wet material the collar is adjusted so that the deepest recesses 64 engage or register with the lug 65 of the frame member 10. In order to facilitate this 80 adjustment I have provided an indicator as shown at 66 which will aid the operator in properly adjusting the mill by letting the indicator 66 on the collar register with marks A, B and C, indicating light, intermediate 85 and heavy spring pressure on the surfaces of the grinding buhrs.

From the above it will be seen that by permitting the collar 60 to be adjusted inwardly with respect to the frame and adjusting thumb nut 61 the pressure on the spring 54 will be correspondingly increased, thereby proportionally increasing the pressure between the grinding surfaces of the buhrs. In other words, by increasing the spring pressure, the sleeve 46 entirely transmits this increased pressure entirely upon the grinding surfaces of the buhrs so that at the same time sufficient pressure will be maintained on the cutter so as to retain them in proper cutting 115 relation, whereby unusual tough, wet or fibrous materials may be readily reduced.

In the drawings I have shown the actuating means comprising a crank handle 67 which has a stub shaft 68 formed integrally therewith. The stub shaft 68 is journaled in a bearing boss 69 formed integrally with the frame member 10. The crank 67 is secured against displacement from the bearing boss 69 by a cotter pin 70. Secured adjacent 120 one end of the stub shaft 68 of the crank handle 67 is a pinion 71 which is in mesh with the gear teeth 72 formed integrally with and on the periphery of the rotating member 27.

From the above it will be seen that when 125

the material is fed in through the hopper 28 it passes into the pocket 24 adjacent the socket 22 and passes through the heart-shaped opening 25 and as the revolving 5 knives 29 are revolved in the direction indicated by the arrow in Fig. 1 to a position where they co-operate with the cutter bar 18, the material is conveyed inwardly toward the axis of the rotating member where it is 10 confined between the cutting member in the form of an ellipse when it is finally cut into relatively large particles, after which they are again recut by the knives 29 and recutting bars 19, 20 and 21, and as the material is con- 15 tinued to be fed it is forced through the opening 30 in the rotating member 29 and by the action of the inclined portions 31 of the knives, the material is forced and fed to a position where it is engaged by the feeding 20 ribs 33 of the rotating member 27 in co-operation with the feeding ribs 39 of the nonrotating member or stationary buhr 37 and by reason of the reversely curved feeding ribs of these respective members the material is 25 forced outwardly to the alternate feeding and sheering ribs adjacent the periphery of these members where it is ground to the reduced form as previously described.

While in the above specification I have 30 described one embodiment of my invention, it will of course be understood that the same is capable of modification and that modification may be employed without departing from the spirit and scope of the invention 35 as expressed in the following claims.

What I claim as my invention and desire to secure by Letters Patent is:

1. A grinding mill comprising a frame and a rotary member journalled on said 40 frame having cutting means on one portion thereof, and separate feeding and grinding means on an opposite portion thereof.

2. A grinding mill comprising a frame and rotary member journalled on said frame having cutting and re-cutting means on one side thereof, and feeding and grinding means on the other side thereof.

3. A grinding mill comprising a frame and a rotary member journalled on said frame 50 having cutting means on one side thereof and feeding and grinding means on the other side thereof.

4. A grinding mill comprising a frame and a rotary member journalled on said frame having cutting means on one side thereof, and feeding and grinding means on the other side thereof, there being an aperture in said 55 rotary member adjacent said cutting means through which the material passes to said feeding and grinding means.

5. A grinding mill comprising a frame and a rotary member journalled on said frame having cutting means on one side thereof, and feeding and grinding means on the other side thereof, there being an aper- 60

ture in said rotary member adjacent the axis thereof through which the material passes to said feeding and grinding means.

6. A grinding mill comprising a frame and a rotary member mounted on said frame having a plurality of spaced apart knives on one side thereof, and feeding and grinding means on the other side thereof, there being a plurality of apertures in said rotary member adjacent said knives through which the 70 cut material passes to said feeding and grinding means.

7. A grinding mill comprising a frame and a rotary member mounted on said frame having a plurality of spaced apart knives on one side thereof, and feeding and grinding means on the other side thereof, there being a plurality of apertures in said rotary member adjacent the axis of said rotary member through which the cut material passes to said 80 feeding and grinding means.

8. A grinding mill comprising a frame and a rotary member mounted on said frame having a curved knife on one side thereof, and feeding and grinding means on the other side thereof, there being apertures in said rotary member adjacent said curved knives through which the cut material passes to said feeding and grinding means.

9. A grinding mill comprising a frame and a rotary member mounted on said frame having a plurality of spaced apart curved cutting knives on one side thereof, and feeding and grinding means on the other side thereof, there being apertures in said rotary member adjacent said curved knives through which the cut material passes to said feeding and grinding means.

10. A grinding mill comprising a frame, a cutter bar mounted on said frame, a rotary member journalled on said frame, a cutter knife carried on one side of said rotary member and co-operating with said cutter bar for cutting the material fed into said mill, and means carried on the other side of said rotary member for feeding and grinding the material cut by said knife and cutter bar.

11. In a grinding machine, the combination of a pair of buhrs, each having a plurality of feeding ribs extending from adjacent the center thereof to the periphery, and a plurality of angularly disposed grinding ribs, whereby the feeding ribs on one buhr co-operate with the feeding and grinding ribs on the other buhr to alternately feed and 110 grind the material passing therebetween, one of said buhrs having cutting means on one face thereof, for cutting material previous to having it ground on the other face thereof.

12. In a grinding machine, the combination of a pair of buhrs, each having a plurality of feeding ribs, certain of said ribs extending from adjacent the center thereof to the periphery, and a plurality of grinding 120

ribs positioned transversely with respect to said feeding ribs whereby the feeding ribs on one buhr co-operate with the feeding and grinding ribs on the other buhr to alternately feed and grind the material passing therebetween, one of said buhers having a plurality of knives on the other face thereof.

13. In a grinding machine, the combination of a pair of buhers, each buhr having a plurality of feeding ribs, certain of said ribs extending from adjacent the center of the buhr to the periphery thereof, there being an aperture through one of said buhers, adjacent said last named rib, and a plurality of grinding ribs positioned transversely with respect to said feeding ribs whereby the feeding ribs on one of said buhers co-operate with the feeding and grinding ribs on the other of said buhers to alternately feed and grind the material passing therebetween, the buhr having the aperture therein being provided with a plurality of cutting knives on one face thereof.

14. In a grinding machine, the combination of a pair of buhers, each having a plurality of feeding ribs extending from the center thereof to the periphery, there being a greater number of feeding ribs on one of said buhers than on the other, a plurality of grinding ribs positioned transversely with respect to said feeding ribs, whereby the feeding ribs on one of said buhers co-operate with the feeding and grinding ribs on the other to alternately feed and grind the material passing between the buhers, one of said buhers being provided with a plurality of knives on one side thereof.

15. A grinding mill comprising a frame, a rotary member journalled on said frame, said rotary member having cutting mechanism on one side thereof and grinding mechanism on the other side thereof, a stationary member mounted on said frame and co-operating with the grinding mechanism on said rotary member, and means whereby the pressure between the grinding surfaces of said members may be proportionately increased over the pressure on said cutting mechanism.

16. A grinding mill comprising a frame, a rotary member journalled on said frame, said rotary member having cutting mechanism on one side thereof and grinding mechanism on the other side thereof, a stationary member mounted on said frame and co-operating with the grinding mechanism on said rotary member, and resilient means whereby the pressure between the grinding surfaces of said members may be proportionately increased over the pressure on said cutting mechanism.

17. A grinding mill comprising a frame, a rotary member journalled on said frame, said rotary member having cutting mechanism on one side thereof and grinding mechanism on the other side thereof, a stationary member

mounted on said frame and co-operating with the grinding mechanism on said rotary member, and means operatively connecting the axes of the rotary and stationary members together whereby the pressure between the grinding surfaces of said members may be proportionately increased over the pressure on said cutting mechanism.

18. A grinding mill comprising a frame, a rotary member journalled on said frame, said rotary member having cutting mechanism on one side thereof and grinding mechanism on the other side thereof, a stationary member mounted on said frame and co-operating with the grinding mechanism on said rotary member, and means movable axially of said members whereby the pressure between the grinding surfaces of said members may be proportionately increased over the pressure on said cutting mechanism.

19. A grinding mill comprising a frame, a rotary member journalled on said frame, the rotary member having cutting mechanism on one side thereof and grinding mechanism on the other side thereof, a stationary member mounted on said frame and co-operating with the grinding mechanism on said rotary member, and means mounted concentrically with the axes of said rotary and stationary members whereby the pressure between the grinding surfaces of said members may be proportionately increased over the pressure on said cutting mechanism.

20. A grinding mill comprising a frame, a cutter bar carried by said frame, a rotary member journalled on said frame having a cutter knife mounted on one side thereof and co-operating with the cutter bar on said frame, a plurality of grinding ribs on the other side of the rotary member, a stationary member mounted on said frame and having grinding ribs co-operating with the ribs on said rotary members, and adjustable spring means whereby the pressure between the grinding surfaces of said members may be varied.

21. A grinding mill comprising a frame, a cutter bar carried by said frame, a rotary member journalled on said frame having a cutter knife mounted on one side thereof and co-operating with the cutter bar on said frame, a plurality of grinding ribs on the other side of the rotary member, a stationary member mounted on said frame and having grinding ribs co-operating with the ribs on said rotary members, and means including a sleeve forming the bearing for said rotary member and an adjustable tension spring for proportionately increasing the pressure on the grinding surfaces of said rotary and stationary members.

22. A grinding mill comprising a frame, a plurality of cutter bars carried by said frame, a rotary member journalled on said frame, and a plurality of cutter knives car-

ried by said rotary member, there being a different number of cutter knives on said rotary member than the number of cutter bars on said frame whereby cutting action of 5 the various cutting members will be consecutive rather than simultaneous.

23. A grinding mill comprising a frame, a plurality of curved cutter bars carried by said frame, a rotary member journalled on 10 said frame, and a plurality of cutter knives carried by said member, said cutter knives being curved in a reverse direction from the direction of the curvature of said cutter bars.

24. A grinding mill comprising a frame, 15 a plurality of curved cutter bars carried by said frame, a rotary member journalled on said frame, and a plurality of cutter knives carried by said member, said cutter knives being curved in a reverse direction from the 20 direction of the curvature of said cutter bars, there being a different number of cutter knives on said rotary member than the number of cutter bars on said frame whereby the cutting action of the various cutting members 25 will be consecutive rather than simultaneous.

25. A grinding machine comprising a frame, a plurality of spaced apart cutter bars mounted on said frame, said cutter bars 30 having their inner portions in the form of the arc of a circle tangent with a small circle concentric with the axis of the frame and outer portions of said bars extending on a straight line tangent with a relatively larger 35 circle concentric with the first circle, a rotary member journalled on said frame and having a plurality of spaced apart knives co-operating with said cutter bars and having their inner ends in the form of the arcs of 40 circles tangent with a circle concentric with the axis of the rotary member and their outer ends the arcs of relatively larger circles, whereby the material fed into said machine is conveyed inwardly by the action of 45 the knives and cutter bar and compressed in the form of an ellipse and then sheared by the cutting members.

26. A grinding mill comprising a frame, a rotary member journalled on said frame having 50 a cutter knife on one side thereof, there being an aperture adjacent said cutter knife,

and conveying means on the other side of the rotary member extending from adjacent said aperture.

27. A grinding mill comprising a frame, a 55 rotary member journalled on said frame and having a plurality of cutter knives on one side thereof, there being apertures adjacent said cutter knives, and conveying means on the other side of said rotary member extending 60 from adjacent said apertures.

28. A grinding mill comprising a frame, a rotary member journalled on said frame and having a plurality of cutter knives on one side thereof, there being a plurality of apertures arranged eccentrically of the axis of 65 said rotary member, and conveying means on the other side of said rotary member extending from adjacent said apertures.

29. A grinding mill comprising a frame, 70 a rotary member journalled on said frame, cutter bars carried by said frame, a plurality of spaced apart curved cutter knives carried by said rotary member and co-operating with said cutter bars for cutting the material 75 passing therebetween, there being apertures adjacent the knives in said rotary member, and conveying ribs on the rotary member on the side opposite the knives for conveying the material cut by said cutting members. 80

30. A grinding mill comprising a frame, a rotary member journalled on said frame, having a plurality of cutting knives on one side thereof, forming material carrying chambers therebetween, there being an aperture in said rotary member through which material passes, and conveying means on the other side of said rotary member adjacent said aperture. 85

31. A grinding mill comprising a frame, 90 a rotary member journalled on said frame, having a plurality of cutting knives on one side thereof forming material carrying chambers therebetween, there being a plurality of apertures located adjacent the axis of said 95 rotary member and a plurality of conveying ribs located on the other side of said rotary member adjacent said apertures.

In testimony whereof I have signed my name to this specification on this 8th day 100 of March, A. D. 1926.

LUDWIG HOLLAND-LETZ.
